UNITED STATES PATENT OFFICE

103,097

DESIGN FOR AN EMBOSSED METAL SHEET

Edgar E. George, Canton, Ohio, assignor to Dura-
Products Manufacturing Co., Canton, Ohio, a
corporation of Ohio

Application February 24, 1936, Serial No. 61,324

Term of patent 3½ years

To all whom it may concern:

Be it known that I, Edgar E. George, a citizen of the United States, residing at Canton, in the county of Stark and State of Ohio, have invented a new, original, and ornamental Design for Embossed Metal Sheets, of which the following is a specification, reference being had to the accompanying drawing, forming part thereof.

Figure 1 is an elevation of one side of an embossed metal sheet, showing my new design;

Fig. 2, a transverse section through the sheet, taken on the line 2—2, Fig. 1;

Fig. 3, a transverse section through the sheet, taken on the line 3—3, Fig. 1;

Fig. 4, an elevation of the reverse side of the embossed sheet from that shown in Fig. 1;

Fig. 5, a section taken on the line 5—5, Fig. 4; and

Fig. 6, a section taken on the line 6—6, Fig. 4.

I claim:

The ornamental design for an embossed metal sheet, as shown.

EDGAR E. GEORGE.
